UNITED STATES PATENT OFFICE.

ELMER E. KILMER AND FRED P. GROTH, OF CHICAGO, ILLINOIS, ASSIGNEES TO INTER-STATE IRON AND STEEL COMPANY, OF CHICAGO, ILLINOIS, A CORPORATION OF ILLINOIS.

WIRE-BLOCK STRIPPER.

Original application filed September 15, 1921, Serial No. 501,008. Divided and this application filed June 21, 1922. Serial No. 569,827.

To all whom it may concern:

Be it known that we, ELMER E. KILMER and FRED P. GROTH, citizens of the United States, residing at Chicago, in the county of Cook and State of Illinois, having jointly 5 invented certain new and useful Improvements in Wire-Block Strippers, do hereby declare that the following is a full, clear, and exact description of the same, reference 10 being had to the accompanying drawings, in which the same reference letters refer to the same or similar parts.

In the accompanying drawings which 15 illustrate embodiments of the several features of our invention, Fig. 1 is a side view showing the stripping-reel in position on a revoluble block; Fig. 2 is a similar view showing the stripping-reel in position above a feeding reel; Fig. 3 is a top plan view 20 of the stripping-reel; Fig. 4 is a sectional view on the line 4—4 in Fig. 3 showing the stripping-reel in place on one of the blocks; and Fig. 5 is similar view showing the stripping-reel collapsed to drop a coil of 25 wire on a feeding-reel.

Our invention consists in the matters hereinafter described and then pointed out in the appended claims, and the present 30 application is a division of our co-pending application filed September 15, 1921, bearing Serial Number 501,008.

In the drawings the reference letter A indicates a draw bench or frame on which are located die-boxes or draw-plates B through 35 which the wire is drawn from suitable feeding-reels C by the revolving drums or blocks D, disposed along the bench in the usual relation to the dies and revolved by the usual mechanism located under the 40 bench including a suitable clutch to connect and disconnect it to each block; only one block is shown, but it is understood that as many may be employed as desired. In the operation of the parts as heretofore constructed the wire is drawn through the first 45 die-box B onto the revolving block D, and after the block is stopped the drawn coil is stripped over its top by the manual labor of the operator who then lifts it away from the bench or places it upon a feeding-reel from which it is drawn through a second die box B to the second revolving block D, and the above manual operations are then 50 repeated; if a third drawing is necessary to

reduce the wire to the desired diameter the 55 coil is placed by the operator on a second feeding-reel from which it is drawn through a third die-box B to the third revolving block D, and the coil is then manually stripped over the top of this block. 60

In order to eliminate this manual labor according to our invention the blocks are constructed to receive a stripping-reel upon which the drawn wire is coiled as the block 65 revolves, and when the block is stopped a 70 conveyer automatically lifts the reel and its coil from the block and transfers them to another feeding-reel for a subsequent drawing or to a pile or truck after the drawing. As shown the blocks D are conical in 75 contour and are provided with a series of slots d in the outer faces of their bodies and in the upper faces of their flared rims d'.

The stripping-reels E are composed of upper open-end drums e slightly smaller 75 in diameter than the bodies of the blocks in order to rest thereon, and legs e' intermediately pivoted at e² in the outer ends of the cross-arms or spider e³ fastened on the interior of the drum. The legs depend 80 below the drum and are bent outwardly below their pivots through apertures in its lower edge, and their lower portions are inclined outwardly from this point to correspond with the taper of the block and terminate in radially projecting or outwardly flared feet e⁴; the legs on each reel correspond in number and circumferentially spaced relation with the slots in the blocks, 85 so that when a reel is in place on the block 90 its legs and feet will lie in the slots and grooves of the block with their exposed surfaces flush therewith as shown in Fig. 4, and the wire will be wound around the outer edges of the legs and will rest upon the 95 outwardly flared feet. The upper ends of the legs are connected by pivoted links e⁵ to a sliding collar or sleeve e⁶ which moves

up and down on a stem or post e⁷ rigidly mounted on the spider or cross-frame e⁸ at 100 the center of the drum; the sleeve is prevented from turning on the post and its reciprocation thereon is limited by a closed slot e⁹ therein engaging a pin e¹⁰ on the post, and the sleeve is provided with a suitable shackle or eye e¹¹ at its upper end to receive a suspending hook m on a conveying cable or chain M. When a stripping-reel 105

hangs by its eye or shackle the weight of the drum will slide the sleeve up to its raised position at the upper end of the post, and this draws the upper ends of the legs inwardly and throws their lower ends outwardly, so that if the reel is then lowered into position on a block its legs and feet will enter the slots of the block and lie flush with its outer portions. When the shackle is released with the reel off the block the sleeve slides down the stem and throws the legs inwardly as shown in Fig. 5 thereby releasing the coil of wire from the reel, and as the movement of the sleeve on its stem is long enough to withdraw the feet inwardly within the circumference of the drum the coil will drop or pass off the reel.

When the coil of wire on the stripping-reel is to be given a further drawing it is delivered from the reel E to a feeding-reel C which is composed of a conical skeleton frame c having a head c' and a flaring base c² mounted on a rotatable platform c³. The height of the frame c exceeds the length of the legs e' and its lower portion is of substantially the same diameter as the drum e so that when a coil of wire is deposited by a stripping-reel on a feeding-reel it retains its form and may be fed off to the next die. When the stripping-reel is lowered to the underneath feeding-reel and the tension of the hanger chain M is released from the shackle e¹⁰ the spider e³ rests on the head c' and the sleeve e⁶ drops on its stem, and as the distance from the pivots of the legs e' to their feet is less than that from the head c' to the base c² the legs of the stripping-reel collapse inwardly and the coil is then supported on the feeding-reel ready for the second drawing, the stripping-reel being then readily withdrawn from the coil. A second stripping-reel being mounted on a block D, the end of the coil from the reel C is passed through the corresponding die and attached to this block which is then revolved. The operations above described are duplicated until the coil on the second stripping-reel is released therefrom. If a third drawing is desired a third stripping-reel is mounted on a block D, and the operations are repeated. At the end of any drawing the reel and its coil may be deposited on a truck or pile, and when the tension of the hanger on its shackle is released the reel collapses and dumps the coil.

We claim:

1. In a device of the class described, a wire-coiling block, a stripping-reel constructed to receive the wire coiled on the block and comprising a drum carrying a central vertical stem, a reciprocating sleeve on the stem, legs pivoted in the drum and con-

structed with coil-supporting ends projecting below the drum, and links pivotally connecting the upper ends of the legs to the sleeve to expand their lower ends to the contour of the block when the sleeve is raised on its stem and to collapse them when the sleeve is lowered. 65

2. In a device of the class described, a wire-coiling block having seats in its periphery, and a stripping-reel comprising a drum, a spider mounted in the drum and carrying a central vertical stem, a sliding sleeve on the stem having a pin and slot connection therewith, legs pivoted on the spider and constructed with coil-supporting ends projecting below the drum, and links pivotally connecting the upper ends of the legs 70 to the sleeve to expand their lower ends into the seats when the sleeve is raised on its stem and to collapse them when the sleeve is lowered.

3. In a device of the class described, a wire-coiling block having seats in its periphery, and a stripping-reel comprising a drum constructed to seat upon the block, a spider mounted in the drum and carrying a central vertical stem, a sliding sleeve on the stem having a pin and slot connection therewith, legs pivoted on the spider and constructed with coil-supporting ends projecting below the drum, and links pivotally connecting the upper ends of the legs to the 80 sleeve to expand their lower ends into the seats of the drum when the sleeve is raised on its stem and to collapse them when the sleeve is lowered. 85

4. In a device of the class described, a feeding-reel having a base and a skeleton frame, and a stripping-reel comprising a drum, a spider mounted in the drum and carrying a central vertical stem, a sliding sleeve on the stem, legs pivoted on the spider and constructed with coil-supporting lower ends, and links pivotally connecting the upper ends of the legs to the sleeve to collapse their lower ends when the spider is seated on the frame and the sleeve is lowered 100 on its stem. 105

5. In a device of the class described, a stripping-reel having pivotally mounted coil-supporting legs, means on the reel to radially expand and collapse the legs, and a feeding-reel having a base and a skeleton frame extending above its base a distance greater than the length of the legs, whereby when the stripping-reel is seated on the frame of the feeding-reel its legs will 115 collapse within the area of the base. 120

In testimony whereof we affix our signatures.
